(57) **CLAIM**

The ornamental design for a backrest, as shown and described.

DESCRIPTION

FIG. 1 is a front perspective view of the backrest;
FIG. 2 is a rear perspective view of the backrest of FIG. 1;
FIG. 3 is a front view of the backrest of FIG. 1;
FIG. 4 is a rear view of the backrest of FIG. 1;
FIG. 5 is a left side of the backrest of FIG. 1;
FIG. 6 is a right side view of the backrest of FIG. 1;
FIG. 7 is a top view of the backrest of FIG. 1; and,
FIG. 8 is a bottom view of the backrest of FIG. 1.
The short-dash broken lines in the figures depict portions of the backrest that form no part of the claimed design. The dash-dot-dash broken lines in the figures represent the boundary of the claimed design and form no part of the claimed design.
